UNITED STATES PATENT OFFICE.

WILLIAM JOHNSON, OF PENN YAN, NEW YORK.

CAR-COUPING.

SPECIFICATION forming part of Letters Patent No. 446,147, dated February 10, 1891.

Application filed June 21, 1890. Serial No. 356,240. (No model.)

To all whom it may concern:

Be it known that I, WILLIAM JOHNSON, a citizen of the United States, residing at Penn Yan, in the county of Yates and State of New York, have invented certain new and useful Improvements in Car-Couplings; and I do hereby declare the following to be a full, clear, and exact description of the invention, such as will enable others skilled in the art to which it appertains to make and use the same.

My invention relates to improvements in car-couplings.

The object of my invention is to produce a simple, durable, and efficient car-coupling that will couple cars automatically, and that may be readily uncoupled without the necessity of incurring the risk and danger of getting between the cars.

My invention consists, briefly, in a novel construction of draw-hook or pin, the said draw-hook being rotatable in a circular plane upon a fixed center or axis extending transversely through the buffer or draw-head of the coupling, the said draw-hook being located in relation to the center upon which it rotates in such position that the pulling strain thereon will not tend to nor cause the said draw-hook to turn or rotate in the direction to uncouple the cars, and in its further adaptation and of the several parts composing the coupling, as will be more fully hereinafter described and set forth, reference being had to the accompanying drawings, in which—

Figure 1 is a vertical horizontal section through the center of my improved car-coupling. Fig. 2 is also a vertical horizontal section designed to show the parts in an uncoupled position. Fig. 3 is a face or front view of my improved car-coupling. Fig. 4 is a transverse section of the rotatable draw-hook shaft or body of my improved car-coupling, taken on the plane indicated by the dotted line xx of Fig. 5. Fig. 5 is a front view, and Fig. 6 a plan view, of the same. Fig. 7 is a plan view of the coupling-link of my improved car-coupling, and Fig. 8 is an edge or side view of the same.

Referring to the drawings, A designates the buffer or draw-head. B is the draw-bar, which may be of the ordinary construction, and adapted to connect the draw-head to the car in the usual manner.

C is the rotatable shaft or body, of which the draw-hook or pin a and stop b form an integral part and rotate therewith.

55

D is a plate or casting hinged or pivoted to the draw-head by the pivot-shaft p , and adapted to be pressed down by the spring e .

E is the coupling-link.

G and G' are levers solidly attached to the rotatable shaft C for the purpose of rotating the draw-hook.

h is a lever adapted to lift the plate D for the insertion of the coupling-link.

t is the abutment-spring plate for the link E 65 to abut against, and which is held in place by the screw g .

S is a retaining-spring attached to the operating-lever G and to the body of the car or coupling.

70

It will be observed that the salient or distinctive feature of my invention is the rotatable draw-hook or pin, the adaptation and construction of which is clearly discernible from an inspection of the drawings. It will 75 be seen that the draw-hook or pin a , which directly sustains the strain or pressure of pulling the cars, is located below or upon one side of the center of the shaft C, upon which it rotates, in such manner or position that the strain upon the said draw-hook, no matter how great, will not and cannot cause it to move or rotate in the direction to uncouple the cars, but that the tendency from said strain is in the opposite direction, and which is prevented 85

by the interior shoulder b^2 of the buffer-casting A. It will also be seen that a material feature of my improved draw-hook is the shelf or body of C, which extends in front of the hook a , and upon which the end of the link is 90 supported, and which is adapted to lift the link up the hook, and thus to facilitate the uncoupling of the cars.

In carrying out my invention the shell or casting A, and which is adapted for both buffer 95 and draw-head, is perforated or bored transversely through, and the cylindrical part of the rotatable body C is turned to fit accurately but free to revolve therein. The said casting A is similar in outward form to the one in ordinary use for pin-and-link connection, but is required to have greater depth to provide the upward and downward inclines or mouth-guides for the entering link, and which adapts

100

the coupling to the varying heights of the cars. The plate or casting D is pivoted to the draw-head A and forms the downwardly-inclined plane or link-guide, and is also adapted, in 5 conjunction with the spring e, to push the link down over the hook and to retain it in a horizontal position when the cars are uncoupled.

The coupling link E has broad cuniform 10 or wedge-shaped ends, and is otherwise of the ordinary construction. The link abutment-spring t is required to have but little flexibility, and is adapted to be removed and renewed when worn out. The back part of the 15 draw-hook a is beveled and forms a part of the upward mouth-incline or link-guide. The shaft o is coupled to the end of the draw-hook shaft C and extends to the side of the car, and is adapted by means of the lever G' 20 to uncouple the cars from the ground. Suitable connections can also be made to uncouple from the top of the cars. The spring S is adapted to return the draw-hook to a coupled position and to retain it thus against the jar 25 of the cars, and to resist the careless or accidental handling of the lever, by which the cars might become uncoupled.

The rotatable hook should be made of steel, having great strength and capable of being 30 hardened to prevent undue wear, and the coupling-links should be of uniform size and length.

It will be observed that my improved car-coupling is adapted to be coupled to cars 35 fitted with the ordinary pin-and-link coupling. I am aware that car-coupling links have been held and suspended in a horizontal position and adapted to slide up or down inclines for the purpose of coupling cars automatically. I do not, therefore, claim such as 40 my invention.

In the drawings I have shown the rotatable draw-hook of my improved car-coupling located below the center upon which it is rotatable as being the natural and desirable position. It is evident, however, that by reversing the entire coupling and changing the operating-lever the same results could be obtained. It will thus be seen that my invention 45 is susceptible of various modifications in its practical application. I do not, therefore, limit myself to the precise form or construction as shown herein.

Having described my invention, I claim—
55 1. In a car-coupling, the described rotat-

able draw-hook or pin a, the point or end of which is at or near the center of rotation, and the body of which extends outward from the said center, and which is adapted to receive the pulling strain thereon between the 60 said center of rotation and the periphery of the supporting-shaft or body C, as and for the purpose specified.

2. In a car-coupling, the combination of the described rotatable shaft C, adapted to be 65 fitted to the buffer or draw-head A, and the draw-hook or pin a, one side of said draw-hook or pin being adapted to form an incline or guide to the coupling-link, as and for the purpose specified. 70

3. The described rotatable shaft C, draw-hook a, and stop b, formed integral and adapted to be fitted to the buffer or draw-head of a car-coupling and to be operated therein, as and for the purpose specified. 75

4. In a car-coupling, the buffer or draw-head A, perforated as described, provided with upward and downward inclined mouth-planes, one of which is fixed and the other movable, as described, and the shoulder b², in combination with the described rotatable draw-hook a, shaft C, and stop b, as and for the 80 purpose specified.

5. In a car-coupling, the combination of the described buffer or draw-head A, perforated 85 as described, the described draw-hook a, rotatable as described, the coupling-link E, adapted to engage with the said rotatable draw-hook, the pivoted mouth-plate or casting D, and the springs e and t, as and for the 90 purpose specified.

6. In a car-coupling adapted to couple cars automatically, the combination of the described buffer or draw-head A, perforated as described, the described shaft C, draw-hook 95 a, and stop b, rotatable as described, the coupling-link E, adapted to engage with the said rotatable draw-hook a, as described, the pivoted mouth-plate D, adapted to operate as described, the pivot-shaft P, the springs e and 100 t, the screw g, the shaft o, the levers G G', the spring S, and draw-bar B, as and for the purpose specified.

In testimony whereof I affix my signature in presence of two witnesses.

WILLIAM JOHNSON.
